KEY SUPPORT

Robert C. Legat, New Britain, Conn., assignor to
 G. E. Prentice Manufacturing Company, New
 Britain, Conn., a corporation of Connecticut

Application August 19, 1932, Serial No. 629,470

6 Claims. (Cl. 150—40)

This invention relates to improvements in key supporting arrangements particularly adapted to be employed in key cases, for example of the conventional leather type. The present invention particularly affords improved supporting means of the general character disclosed in the United States patent to George E. Prentice No. 1,564,021 and my prior Patent No. 1,564,004, said supporting means, however, being adapted to permit the application of a key to a supporting hanger with greater facility, to permit the more convenient selection of a key from the group of keys supported by the case, and to facilitate the flat disposition of the keys within the case, so that there is little tendency for objectionable bunching or overlapping of the keys. The prior patents identified above disclose key supporting means including hangers having swiveled and substantially universal joint connections with the supporting plate to permit the convenient movement of any individual key in relation to the plate, and thus to facilitate selection of an individual key and its insertion in a suitable keyhole.

The present invention not only retains this advantageous arrangement, but also affords an improved form of hanger which is provided with such a shape that it permits the ready engagement of a key with the resilient hook or hanger despite the swiveled supporting of the hook upon the plate. Furthermore, the present invention affords an improved supporting plate which is particularly advantageous with swiveled supporting means of the type referred to in facilitating the positioning of the hangers in normal side by side relationship within the casing, so that they normally are prevented from objectionably moving into overlapped relationship, and so that the keys supported thereby tend to group themselves into a relatively flat assembly, rather than objectionably bunching, catching upon each other, and the like. The supporting plate also particularly cooperates with the improved form of hanger in facilitating the initial engagement of a key with a selected hanger.

To permit these desirable results, each hanger is provided with an outwardly bowed end portion, which has the general form of a peripheral portion of a circle, and with a corresponding shank portion which cooperates in providing a recess of substantial size in which the end of a key may readily be received so that the key is guided into a position to spread the legs of the resilient hanger and is thus brought into proper engagement therewith.

Furthermore, the supporting plate is provided

with a plurality of spacers or outwardly bowed portions below the loops, which engage the hanger supports, these bowed portions being effective in maintaining the hanger supports in spaced parallelism when the keys are in their normal position within the case. 5

Due to the swiveled mounting of the hanger supports, the hangers and keys may be readily swung away from this position when the case is opened to facilitate selection of any desired key, 10 and its insertion within a keyhole.

In the accompanying drawing:

Fig. 1 is a front elevational view of my improved key hanger assembly showing the same secured to a conventional enclosing case, the latter being in its open position and certain hangers being broken away; 15

Fig. 2 is an end elevation of the hanger assembly shown in Fig. 1;

Fig. 3 is an enlarged transverse sectional view 20 on the line 3—3 of Fig. 1;

Fig. 4 is a front elevation of a blank from which the improved hanger supporting plate may be formed;

Fig. 5 is an elevational view showing the manner in which the hanger supports may be maintained in parallelism, or if desired, any selected support may be swung out of such a position; 25

Fig. 6 is a sectional detail showing a hanger support and related parts; and 30

Fig. 7 is an elevational detail showing the form of a blank from which a hanger support may be made.

Referring to the drawing, numeral 1 indicates a conventional key case which may be formed of 35 leather or the like and is provided with a body portion to which a supporting plate 10 is secured by fastening elements such as rivets 11, the case being provided with flaps 12, which normally are fastened in overlapping position when the case is 40 closed.

In accordance with this invention, the plate 10 may be formed from a flat sheet metal blank 10^a of the general character illustrated in Fig. 4. This blank is provided with a plurality of parallel 45 fingers 14^a projecting from its upper edge, and has opposite outstanding ears 15^a which preferably have a greater width at their outer extremities than at their regions of juncture with the body portion of the blank. Beneath the fingers 14^a, as shown in Fig. 4, the blank may be provided with a plurality of rectangular openings 19^a separated by parallel metal bar portions 20^a. Adjoining the ends of the blank, openings of more restricted size, designated by reference charac- 50 55

ter 19^b, may be provided, and tabs 21^a having openings therein may be provided so that bars 20^a are afforded adjoining the end of the blank similar to the bars in the intermediate part thereof.

A blank of the character illustrated in Fig. 4, may then be shaped so that the bars 20^a are bowed inwardly from the general plane of the blank, and so that the fingers 14^a are bent downwardly and inwardly to afford loops, while the ears 15^a may be bent inwardly at right angles to the general plane of the blank, so that their outer extremities lie substantially in the plane of the rear face of the planar body portion of the blank. Thus, for example, as shown in Figs. 2, 3 and 6, the blank is provided with a plurality of outwardly bowed bars 20 formed from the bar portions 20^a with abutment elements 15 at either end of the bowed portion adapted to engage the surface of the case 1, and with a plurality of loops 14 to support the ends of the hanger supports. The tabs 21^a of the blank are retained as tabs 21 (Figs. 1 and 3) in the general plane of the blank, and thus may engage the body portion of the casing and receive the rivets 11 at each side of the supporting plate.

Each loop 14 preferably engages a hanger support 25 of the character which is described in the above-identified patents. The lower end of each hanger support engages a hanger 30 which may be in the general form of a resilient wire hook having one leg terminating slightly below the hanger support.

As more fully described in the above-identified patents, the upper end of each hanger may be provided with a wire eye or loop 31 disposed within a ball-like recess 32 in a hanger support 25. The latter is preferably formed from a flat blank 25^a having a body portion which is substantially square but provided with a central opening 26^a and with diagonally opposite perforated ears 27^a. This blank is bent into a suitable form to afford a substantially ball-like recess which receives the hanger eye 31 with the perforated portions 27^a registering with each other and engaged by a loop 14 of the supporting plate. Below the eye or ball-like portion 31 the hanger 30 is provided with an inwardly bowed or bulged portion 34 (Fig. 6), which has a curvature that may substantially correspond to that of the portion of a circle. Below the bulged portion 34 the hanger is provided with a loop 36, and the opposite leg thereof inclines upwardly and inwardly to provide a portion juxtaposed to the part of the wire below the bulge 34. Above this portion of the shorter leg is an outwardly curved or bulged end portion 38 having a curvature substantially corresponding to that of the bowed portion 34. Thus the portions 34 and 38 cooperate in providing a key-receiving recess in which the end portion of the key is readily received despite the swiveled mounting of the hanger.

As shown in Fig. 5, the hanger supports 25 normally tend to lie between the spacing bars 20, either under the action of gravity or due to the retaining effect of the flaps 12 when the case is closed. When the case is opened, however, one of the keys may be picked out and swung about its connection to the plate, so that the hanger support no longer lies between the adjoining bars 20, thus permitting the swinging of the hanger in any desired direction. For example, as shown in Figs. 1 and 5, the support upon the left of the assembly is thus moved out of its normal position in relation to the supporting plate.

The initial engagement of a key with a hanger is facilitated by the arrangement of the spacing bars 20. The hanger support may be held in the recess between the corresponding spacers 20 by one hand and the key engaged with the recessed end of the hanger with the other hand while the bars prevent objectionable lateral movement or swiveling of the hanger. For this purpose the supporting plate and hanger support may be gripped between the thumb and forefinger of one hand while the key is brought into initial engagement with the bulged portions 34 and 38 of the hanger with the other hand, and is pressed downwardly to spread the juxtaposed portions of the hanger apart so that the key is readily brought into engagement with the bottom loop portion of the hanger. Similarly when a key is to be disengaged from its hanger, the retention of the hanger support between the spacer bars is advantageous. It is accordingly evident that the present invention permits the advantageous freedom of movement of the key hangers and keys, which is a characteristic of key supporting assemblies constructed in accordance with the above-identified Prentice and Legat patents, but that objectionable freedom of movement will be avoided when a key is to be engaged with or disengaged from the hanger or when the case is closed and the keys are being carried in a pocket, pocketbook or the like.

I claim:

1. A key supporting assembly for key cases or the like, comprising a supporting plate having a generally planar body portion and having an outwardly bowed portion above said body portion and extending between its opposite sides, openings in said bowed portion between a plurality of bowed bar portions, key hangers having upper ends with swiveled connections to the upper part of said plate including loops above said bowed portion, the bar portions being arranged so that they normally hold the upper ends of the hangers in mutually spaced relation when the lower parts of the hangers lie in juxtaposition to the body portion of the plate, and fastening tabs to secure the plate to a case or the like, said tabs being disposed between certain of said bar portions and lying in the plane of said body portion.

2. A key supporting assembly for a key case or the like comprising a supporting plate having a generally planar body portion with fingers upon its upper edge bent over to afford loops and having an outwardly bowed portion between said fingers and said body portion, openings in said bowed portion between a plurality of bowed spacer bars, hanger supports having eyes in swiveled engagement with said loops, and key hangers of resilient wire, said hangers each having a generally ball and socket-like engagement with a corresponding hanger support, the spacer bars being arranged so that they normally hold the hanger supports in mutually spaced relation when the lower parts of the hangers lie in juxtaposition to the planar body portion of the plate.

3. A key supporting assembly for a key case or the like comprising a supporting plate having a generally planar body portion with fingers upon its upper edge bent over to afford loops, and having an outwardly bowed portion between said fingers and said body portion, openings in said bowed portion between a plurality of bowed spacer bars, hanger supports having eyes in swiveled engagement with said loops, and key hangers of resilient wire, said hangers each having a generally ball and socket-like engagement with a corresponding

hanger support, the spacer bars being arranged so that they normally hold the hanger supports in mutually spaced relation when the lower parts of the hangers lie in juxtaposition to the planar body portion of the plate, each of said hangers being in the general form of a hook with one leg connected to the corresponding hanger support and the other leg having a free end to engage the end of a key, said last-named leg having a bowed portion adjoining its free end to afford an enlargement to facilitate the engagement with a key.

4. A key supporting assembly for a key case or the like comprising a supporting plate having a generally planar body portion with fingers upon its upper edge bent over to afford loops and having an outwardly bowed portion between said fingers and said body portion, openings in said bowed portion between a plurality of bowed spacer bars, hanger supports having eyes in swiveled engagement with said loops, and key hangers of resilient wire, said hangers each having a generally ball and socket-like engagement with a corresponding hanger support, the spacer bars being arranged so that they normally hold the hanger supports in mutually spaced relation when the lower parts of the hangers lie in juxtaposition to the planar body portion of the plate, each of said hangers being in the general form of a hook with one leg connected to the corresponding hanger support and the other leg having a free end to engage the end of a key, said last-named

leg having a bowed portion adjoining its free end to afford an enlargement to facilitate the engagement with a key, the other leg of each hanger having an oppositely bowed portion co-operating with the first-named bowed-in portion in affording a recess or enlargement to receive a key when it is initially engaged with a hanger.

5. A key-supporting assembly for key cases or the like comprising a sheet metal supporting plate, pivot means at the upper margin of the plate including spaced tubular loop portions of the plate, a plurality of key hangers, hanger supports swiveled to said means and each having an articulated connection with the upper end of one of the hangers, each articulated connection permitting limited universal movement of the hanger and its support, said plate having spacer bars bowed outwardly below said loop portions to lie between the supports and normally hold the same substantially parallel so that the upper ends of the hangers are maintained in spaced relation.

6. A key-supporting assembly for key cases or the like comprising a sheet metal supporting plate, a plurality of key hangers, articulated connections between the hangers and plate including loop portions of the plate at its upper margin, said plate having spacer bars bowed outwardly below said loop portions to hold the upper parts of the hangers in spaced relation when the hangers are juxtaposed to the lower part of the plate.

ROBERT C. LEGAT.
